CONTAINER

Alfred A. Wescott, Elmira, N. Y.

Application May 29, 1936, Serial No. 82,633

8 Claims. (Cl. 259—72)

This invention relates to containers, and more particularly to containers for materials consisting of mixed solids and liquids such as paint and the like, in which sedimentation or settling 5 occurs upon standing.

As is well known, in the case of paint, for example, after standing for considerable periods the solid materials, no matter how finely divided, settle to the bottom of the ordinary can or 10 container, forming a compact mass which is dislodged and remixed with the liquid ingredients only with considerable difficulty. In the usual case it is necessary, after removing the lid of the container, to pour off a part of the liquid, 15 to avoid spilling, and to stir the solid materials with the remaining liquids, using a rod or other implement, for a considerable period of time before a satisfactory mixture is obtained. It is then necessary to mix in the remainder of the 20 liquid, either by further stirring or by pouring the materials from one container to another until a satisfactory mixture results. These operations are time-consuming, wasteful and messy, and furthermore result, usually, in an incomplete 25 suspension of the solids, a certain proportion of which continues to adhere to the bottom and sides of the container.

One object of the present invention is to provide means for preventing the solid ingredients 30 of paint and similar materials from concentrating at the bottom of the container. A further object is the provision of means whereby the ingredients of paint and the like, after standing for considerable periods, may be thoroughly 35 mixed with facility and before the container is opened. Other and further objects, features and advantages will appear from the description which follows, together with the accompanying drawing, in which:—

Fig. 1 is a vertical sectional view of a container in accordance with the present invention; and

Fig. 2 is a horizontal section on line 2—2 of Fig. 1.

The device comprises in general a container member 1, of sheet metal or other suitable material, such as the ordinary paint can, having a conventional lid 2, upon the under side of which is secured a mixing device 3. In the embodiment illustrated, the lid 2 is secured to the container member 1 by means of a conventional friction seal, but it will be understood that a threaded closure may be substituted if desired, or any other suitable means may be employed for securing the lid 2 to the container member 1.

Likewise the latter may take any suitable form in addition to the cylindrical form illustrated, and may be fabricated of any suitable material. For example, it may be desirable in certain cases to make the container member 1 of glass, so that 5 the progress of the mixing operation may be observed without opening the container.

The mixing device 3, secured to the underside of the lid 2 in any suitable fashion, comprises a generally cylindrical supporting member 4 and a series of baffles 5 secured to the inner side of the member 4 at suitable intervals along its height. Three such baffles 5 are shown in the present embodiment, but it is obvious that the member 10 may be varied in accordance with the size and 15 shape of the container and the nature of its intended contents.

The supporting member 4 is preferably slightly tapered, as shown, to facilitate removal from the container and to avoid dripping upon the 20 flanges of the container when the lid and mixing device are removed. The member 4 and baffles 5 are preferably integral, and may be made of any suitable material which is compatible 25 with the intended contents of the container and which is sufficiently rigid for the purpose set forth below, sheet metal being a suitable material in the case of paint.

The member 4 is pierced by a number of perforations 6, preferably serrated as shown. The 30 perforations 6 may vary in size and shape, according to the intended contents of the container, and may be arranged in rows, as shown, or irregularly.

The baffles 5 are preferably frusto-conical in 35 form, as shown, and are likewise pierced by a plurality of perforations 7, similar to the perforations 6. The upper edge 8 of each baffle, defining the central opening 9, is also preferably serrated. When baffles such as those shown are 40 employed, having an outward and downward inclination, the perforations 6 should be so arranged that one or more of such perforations has its lowest point at or about the line of junction between each baffle 5 and the member 4, 45 thus providing an outlet for draining each baffle as the mixing device is withdrawn from the container.

From the foregoing description the operation 50 of the device will be apparent. When the container is charged with a mixture of solids and liquids in suspension, and the lid and mixing device put in place, it will be impossible for all of the solid ingredients to settle on the bottom of the container, as a large proportion of such 55

materials will in settling, come to rest upon one or the other of the baffles 5, the solid materials thus being divided between the bottom of the container and the several baffles. When it is desired 5 to make the contents available for use, it is only necessary to shake the container, when the liquid ingredients, jetting through the perforations 6 and 7, will dislodge the solid material from the bottom and walls of the container member 1 and 10 the surfaces of the mixing device 3, and cause it to become thoroughly mixed with the liquid ingredients. In charging the container, it is preferred not to fill it completely, but to leave a certain proportion of the enclosed space unoccupied, thus enabling a better and quicker mixing 15 action than if the container is completely filled.

After the contents have been adequately mixed, the lid 2 is removed, bringing with it the mixing device 3, which is suspended momentarily over 20 the open mouth of the container to permit it to drain thereinto. The contents are then ready for use.

It will be apparent that many variations of 25 the several elements of the container and mixing device are possible, without departing from the scope of the present invention. For example, for applications in which the contents are to be removed to a second container before using, the mixing device might be secured to the 30 container member instead of the lid. Also, if desired, the mixing device might be made entirely separate from the container and lid.

Having thus described the invention, what is 35 claimed as new and desired to be secured by Letters Patent is:

1. In a device of the character described, a container, a lid for closing said container, and a mixing device secured to said lid and comprising a hollow perforated supporting member and 40 a plurality of perforated baffles extending transversely of said supporting member and secured thereto at spaced intervals.

2. In a device of the character described, a container, a lid for closing said container, and a 45 mixing device comprising a hollow perforated

supporting member and a plurality of perforated frusto-conical baffles extending transversely of said supporting member and secured thereto at spaced intervals.

3. In a device of the character described, a 5 container, a lid for closing said container, and a mixing device secured to said lid and comprising a hollow perforated supporting member and a plurality of perforated frusto-conical baffles extending transversely of said supporting member 10 and secured thereto at spaced intervals.

4. In a device of the character described, a 15 container, a lid for closing said container, and a mixing device secured to said lid and comprising a hollow perforated supporting member and a plurality of perforated frusto-conical baffles extending transversely of said supporting member and secured thereto at spaced intervals, a perforation being arranged in said supporting member adjacent the lowest point of each baffle. 20

5. In a device of the character described, a 25 container, a lid for closing said container, and a mixing device secured to said lid and comprising a tapered hollow perforated supporting member and a plurality of perforated baffles extending transversely of said supporting member and secured thereto at spaced intervals.

6. In a device of the character described, a 30 hollow supporting member provided with a plurality of perforations having serrated edges, and a plurality of perforated baffles secured transversely within said supporting member.

7. In a device of the character described, a 35 hollow perforated supporting member, and a plurality of perforated baffles secured transversely within said supporting member, the perforations of said supporting member and baffles having serrated edges.

8. In a device of the character described, a 40 hollow supporting member having a plurality of transverse baffles secured therein, said supporting member and baffles each having a plurality of stellated perforations.
